DENTAL EXAMINATION MIRROR

John S. Cali, 3452 E. Foothill Blvd.,
Pasadena, Calif. 91107

Filed Sept. 16, 1974, Ser. No. 506,010

Term of patent 14 years

Int. Cl. D24—02

U.S. Cl. D24—1 D

FIG. 1 is a top perspective view of a dental examination mirror showing my new design;

FIG. 2 is a bottom perspective thereof; and

FIG. 3 is an enlarged fragmentary view of the distal end of the handle member.

I claim:

The ornamental design for a dental examination mirror, as shown and described.
